UNITED STATES PATENT OFFICE.

JOHN F. COURSON, OF PITCAIRN, PENNSYLVANIA.

DRAFT-GEAR.

1,337,002.

Specification of Letters Patent. Patented Apr. 13, 1920.

Application filed December 11, 1916. Serial No. 136,142.

To all whom it may concern:

Be it known that I, JOHN F. COURSON, a citizen of the United States, residing at Pitcairn, in the county of Allegheny and 5 State of Pennsylvania, have invented certain new and useful Improvements in Draft-Gears, of which the following is a specification.

My invention is an improvement in draft 10 gears of the class utilizing springs and friction shoes and expanding mechanism for the friction shoes, operable on buffing or pulling, to effect resistance to such strains through the mechanism inclosed within an 15 embracing cylinder or casing.

The particular objects in view are to provide, in a gear of this type, means for distending the friction shoes toward the casing with frictional engagement proportioned to 20 the strain, utilizing movable elements between a central plunger and the friction shoes, whereby to effect expansion or retraction of the shoes coincidental with pressure and release movements. These elements operate in the manner of tightening 25 and loosening bearings of the toggle joint type.

The several objects are accomplished in certain preferred forms of the apparatus, 30 as more fully hereinafter described and illustrated in the accompanying drawings, in which—

Figure 1 is a longitudinal vertical sectional view through a complete gear as assembled, the parts being shown in normal extended position.

Fig. 2 is a similar view, showing the parts in compression, either in buffing or pulling.

Fig. 3 is a cross section on the broken line 40 III, III of Fig. 1.

Fig. 4 is a perspective detail view of the central pressure bar.

Fig. 5 is a similar view of one of the friction shoes.

45 Fig. 6 is a similar view of one of the intervening movable pressure exerting and transmitting members.

Fig. 7 is a view similar to Fig. 1, showing a modified construction, in relaxed or 50 normal position.

Fig. 8 is a similar view, showing the parts in compression.

Fig. 9 is a detail perspective view of one of the friction shoes as used in the gear of 55 Figs. 7 and 8.

Fig. 10 is a similar view of one portion

of the centrally arranged compound pressure bar.

Fig. 11 is a cross sectional view on the line XI, XI, of Fig. 7. 60

Fig. 12 is a perspective detail view of one of the intervening movable pressure exerting and transmitting members used with the construction of Figs. 7 and 8.

Fig. 13 is a sectional detail view showing 65 the face of one of the compound pressure bar members having a rounded abutting bearing against the other.

Fig. 14 is a partial detail sectional view 70 similar to Figs. 1 to 4 inclusive, but showing the utilization of a roller bearing member interposed between the central pressure bar and the friction shoes.

Fig. 15 is a perspective detail view of the extension member of the compound pressure 75 bar.

In the drawings, 2 represents the draw bar of a coupler connected with the front end portions of side links 3 by a transverse bolt or key 4 which extends through slots 5 in the front portion thereof, its ends preferably terminating within the inner faces of the center sills 7 of the car framing at 80 each side, for longitudinal movement. Links 3 are longitudinally slotted at their rear ends, as indicated at 8 Fig. 3, and engage lugs 9, of the casing or cylinder 10 mounted between the center sills 7 for limited movement in buffing. Casing 10 is closed at its rear end and normally presses against the 90 rear abutment 11, while a follower 12 at the front end is adapted to oppose forward movement of the casing in pulling. Said follower engages against stops 13 of the center sills in forward movement under 95 draft or pulling strains, and is pushed back by the rear end of draw bar 2 in buffing.

Within the casing are friction shoes 14 which bear by their inner ends against a spring or springs 15, it being noted that a 100 plurality of said shoes are arranged within the casing.

Each of the shoes 14 is provided, preferably at or near its front and rear portion, with a concaved or rounded recess or socket bearing 16, entirely within the body portion of the shoe, adapted to receive the similarly rounded face of an intervening movable pressure exerting member 17, having at its opposite side an extending rounded portion 110 engaging a similar rounded receiving recess 18 of the centrally arranged pressure bar 19.

Said pressure bar, as shown in Figs. 1 and 2, is a single integral member, bearing by its front end against follower 12 and is operative in connection with members 17, to 5 actuate them in the manner of a toggle joint to distend the shoes 14 into frictional engagement with the casing 10, either in buffing or pulling.

The parts being comparatively closely adjusted, a comparatively small degree of longitudinal movement of member 19 is necessary to distend the shoes into tight frictional engagement with the casing, after which the shoes will move within the casing in buffing, 10 or the casing upon the shoes, in pulling, with a frictional resistance proportionate to the strain, any increase of pressure acting to distend the shoes more tightly against the casing.

20 Members 17, as shown in Figs. 1 and 2, are generally of oval form in cross-section, their longest diameter being on the line a, a' , as indicated in Fig. 1. The angle of such line to the longitudinal center line b, b' , of 25 the gear is sufficiently acute to prevent any locking of the gear at the maximum pressure and distention and to facilitate a prompt and free release, due to the action of springs 15 upon release of pressure.

30 In Figs. 7, 8, 10, 13, 14 and 15 the construction is generally the same as just described except that the central pressure bar is made as a compound member consisting of a main bar 19^a and a supplemental bar 19^{a'}. Said supplemental bar is in abutting 35 engagement with the inner end of bar 19^a and forms an extension of it, and by making the central pressure bar as a compound bar member, I provide sufficient flexibility to insure 40 against any inequality of strain as to the several intervening movable pressure exerting members 17^a. That is to say, the flexibility of the compound central pressure bar allows said members 17^a to adapt themselves within the friction shoes 14^a to compensate for any inequality as to fitting, or 45 on account of wear, or other causes.

The intervening members 17^a are generally similar in construction and operation 50 to members 17 of Figs. 1 and 2, but are shown as being provided with outer rounded bearing portions 17^{a'} of a maximum radius and bearing surface, as compared to the somewhat smaller inner rounded bearing 55 faces 17^{a''} which engage the corresponding sockets 18^a of the pressure bar members. The advantage of this arrangement is that it provides for compact construction and insures maintenance of the parts in operative 60 position.

In Fig. 13 the supplemental pressure bar member 19^{a''} is shown as provided with a rounded face 19^{a'''} abutting against the confronting flat face of the main pressure bar 65 member 19^a, providing the flexibility above

mentioned by a rolling bearing, and insuring against any undue stiffness or rigidity.

In Fig. 14 I show a still further modification in which the recesses 16^b of the friction shoes 14^b are somewhat enlarged as to 70 their radius and provide concave rolling bearing faces for intervening rollers 17^b. These bear by their opposite sides against the concave bearing faces 18^b of the central pressure bar 19^b and its extension 19^{b'}. The 75 action in such case is substantially the same, except that the rollers 17^b act with the usual effect with roller bearings, reducing friction and without any toggle action, merely providing for transmission of pressure to the 80 friction shoes due to the advancing laterally pressing rounded faces of the central pressure bar or of the friction shoes.

The construction and operation of the gear will be readily understood from the 85 foregoing description and it will be found to provide a simple, highly efficient and effective means for exerting great frictional resistance.

What I claim is:

1. A draft gear consisting of a casing, a pair of oppositely located friction shoes within the casing having interior fore and aft bearing recesses, a central compound pressure bar comprising fore and aft abutting sections each provided with recesses, and intervening loosely mounted pressure transmitting members engaging the recesses of the friction shoes and pressure bar respectively. 90

2. In combination, a casing, friction shoes within the casing having interior fore and aft bearing recesses, a draw bar and follower in operative relation to the casing, a central compound pressure bar composed of fore 95 and aft abutting sections extending inwardly between the friction shoes and each provided with outer recesses, loosely mounted pressure transmitting members between the friction shoes and the pressure bar and engaging the recesses thereof, and a spring 100 within the casing engaging the friction shoes. 110

3. In combination, a casing, friction shoes within the casing having interior fore and aft bearing recesses, a drawbar and follower in operative relation to the casing, a central compound pressure bar composed of abutting sections extending inwardly between the friction shoes and provided with 115 an intervening flexible joint bearing and corresponding outer fore and aft bearing recesses, loosely mounted pressure transmitting members between the friction shoes and the pressure bar and engaging the recesses 120 thereof, and a spring within the casing engaging the friction shoes. 125

In testimony whereof I hereunto affix my signature.

JOHN F. COURSON.
